CHRISTMAS ORNAMENT OR THE LIKE

Dario Moranduzzo, Via Aretina 161, Florence, Italy

Filed Sept. 22, 1966, Ser. No. 3,984

Term of patent 14 years

(Cl. D29—1)

FIG. 1 is a front perspective view of a Christmas ornament or the like;

FIG. 2 is another front perspective view thereof as it appears with the cover removed; and

FIG. 3 is a rear perspective view of the cover portion thereof.

I claim:

The ornamental design for a Christmas ornament or the like, as shown.
